(57) **CLAIM**

The ornamental design for a CMX insulating jacket accessory as shown and described.

DESCRIPTION

FIG. 1 is a top perspective view of a CMX insulating jacket accessory;

FIG. 2 is a front elevational view thereof, the rear being a mirror image;

FIG. 3 is a left side elevational view thereof, the right side being a mirror image; and,

FIG. 4 is a bottom perspective view thereof.

The broken lines depict portions of the CMX insulating jacket accessory that form no part of the claimed design.
